UNITED STATES PATENT OFFICE.

JOHN L. MOHUN, OF BROOKLYN, NEW YORK.

CAR-ROOF CONSTRUCTION.

1,077,633.

Specification of Letters Patent.

Patented Nov. 4, 1913.

Application filed December 21, 1911. Serial No. 667,071.

To all whom it may concern:

Be it known that I, JOHN L. MOHUN, a citizen of the United States, residing at Brooklyn, in the county of Kings and State 5 of New York, have invented new and useful Improvements in Car-Roof Construction, of which the following is a specification.

This invention relates to car roof construction, some of the features being particularly applicable to roofs for refrigerator 10 cars, while other features may also be employed in connection with roofs for other types of freight cars.

One of the objects of my present invention is to provide a wooden carline having a metal trough mounted thereon, which may also serve as a metal carline for supporting the metal roofing sheets and receive the drainage therefrom, the side edges of said 20 roof sheets being adapted to drain into the metal troughs or carlines.

Another object is to provide an improved rain proof hatch, or ice door construction in the refrigerator car roof.

25 Another object is to provide an improved longitudinal member, such as the ridge pole or purlin, built up in sections connected together over the drain troughs or carlines; and still another object is to provide the 30 metal ridge pole with a turned down flaring end, having side flanges for bolts for fastening to the end plate, and extending over the end plate and out upon the top of the facia board.

35 In the accompanying drawings: Figure 1 is a transverse section of a portion of a car roof embodying certain features of my improvement; Fig. 2, a transverse section of a carline and running board saddle, taken on the line 2—2 of Fig. 1; Fig. 3, a similar section of a carline, taken on the line 3—3 of Fig. 1; Fig. 4, a transverse section of a portion of the roof, taken through one of the hatches; Fig. 5, a plan of the hatch with a 40 corner of the door broken away; Fig. 6, a plan showing a portion of my improved sectional ridge pole; Fig. 7, a side elevation of the same; Fig. 8, an end view of one of the ridge pole sections; Fig. 9, an end view of 45 the ridge pole; and, Fig. 10, a transverse section of the ridge pole on a larger scale, taken on the line 10—10 of Fig. 7.

Referring to Figs. 1 to 3, the supporting frame-work of the car roof may comprise 50 the wooden carlines, 20, having the metal troughs or U shaped carlines, 20^a, mounted

or embedded therein with the upper flange substantially flush with the top of the wooden carline and the roofing boards, 30, which may be located between the carlines 60 and supported on strips, 20^b, fastened to the sides of the wooden carlines below the top surface thereof. The metal roof sheets, 23, may then be laid upon the roofing boards and have the side edges of the sheets turned up and over to drain into the troughs of the carlines, the turned over edges and carlines being covered by carline caps, 22, which are held at their lower ends by the carline hoods, 60, bolted to the carlines and side 70 plate. The upper edges of the roof sheets are also turned over to drain into the trough of the U shaped metal ridge pole, 25, having flaring flanges, 25^a, bearing against the under side of the roof sheets, and supported 75 upon the carlines. A ridge cap, 33, covers the upper ends of the roofing sheets and the trough in the ridge pole.

The running board saddle, 40, for supporting the running boards, 41, is formed 80 separate from and bolted to a central web portion, 31, which extends down into the carline where it is fastened by bolts beneath the roofing boards, 30. In the construction of refrigerator cars, it is customary to put 85 in the carlines with the double ceilings, 44, and felt linings, 45, and the roofing boards, 30, before the outside metal roof is applied, and with my improved saddle formed in two parts, as shown, the web portion, 31, may 90 be bolted in position before the roofing boards are put on, then after the roofing boards are applied, the metal roofing sheets, carline caps and ridge cap may be placed in position, and the running board saddle, 40, 95 then bolted to the web, 31, thereby covering the ends of the ridge cap and the carline caps and holding the same in place.

As shown in the drawing, the wooden carline, 20, is preferably formed of two side timbers, and an intermediate spacing piece bolted together, the metal drain trough or carline, 20^a, being mounted with its top flanges resting on the side timbers, and the trough portion extending down between the same to the top of the intermediate spacing block. This forms a strong construction in which the metal trough or carline is thoroughly insulated, but it will be evident that the carline may be constructed in other ways, 105 if desired.

Refrigerator cars are usually provided

with hatches in the roof, which are formed by means of hatch timbers, 50, carried by the carlines and roof members, as shown in Fig. 4, and projecting above the outside surface 5 of the roof. When metal roof sheets are used and the same are bent up against and fastened to the hatch frame, the weaving motion of the car, which causes a twisting movement between the hatch frame and the 10 roof, soon produces a cracking of the roof sheet at the bend, thereby causing a leak. According to one feature of my improvement, this is prevented by providing the roof sheets, 23, with turned up edges, 23^a, 15 about the sides of the hatch frame, 50, but detached therefrom, and having a clearance space between the same to allow for a free relative movement. In order to prevent the entrance of rain or snow into this clearance 20 space, I provide a metal covering or hood, 51, fastened upon the top of the hatch frame, and having its outer edge bent down over the up-turned edges of the roof sheets, but at a slight distance therefrom, in order to provide the necessary flexibility. This metal 25 frame or hood is preferably divided into a number of straight angular bars corresponding to the number of sides of the hatch frame, and each provided with interlocking 30 lugs, 52, at its ends, adapted to be pivotally fastened together by pins or rivets at the corners of the frame. By means of this construction, the metal frame may automatically adjust itself to the movements of 35 the hatch frame. The hatch door, 53, may then be mounted on hinges, 54, carried by the metal hood, 51, and be secured by a clasp in the usual way.

For the purpose of facilitating the handling of the longitudinal roof members such 40 as the metal ridge pole, 25, I prefer to construct the same in a series of sections, as shown, particularly in Figs. 6 to 10 of the drawings. Each of the intermediate sections 45 is provided at its ends with flanges, 25^b, bent outward at right angles and arranged to be riveted to the flanges of adjacent sections over the drain troughs of the carlines, 20^a, an opening, 25^c, being left between the abutting flanges at the bottom 50 of the ridge pole for permitting the water to drain out into the trough of the carline. The outside end of the end section may also be provided with wide lateral flanges, 25^d, 55 for bolting to the end plate, and a flaring lower flange, 25^e, extending out over the end facia board. By means of this feature of my improvement, the metal ridge pole may be formed of pressed U shaped metal 60 sections, and be more readily handled and shipped without danger of breaking, bending or otherwise injuring the same. While I have illustrated this feature as applied in connection with a refrigerator car roof, it

will be evident that it may also be equally well applied to other forms of car roofs.

By means of my improved construction, including the metal drain troughs or carlines, 20^a, mounted on and embedded in the wooden carlines, it will be seen that all of 70 the metal roof parts are insulated from the space beneath the roof, while at the same time, an effectual drainage system is provided for preventing leakage.

Having now described my invention, what 75 I claim is new, and desire to secure by Letters Patent, is:—

1. In a car roof, the combination of a wooden carline having a metal drain trough mounted thereon the wooden carline covering the sides of said trough, and metal roof sheets having their side edges adapted to drain into said trough. 80

2. In a car roof, the combination of wooden carlines having metal drain troughs 85 or carlines mounted thereon, roofing boards supported by said carlines substantially flush with the top of the trough, and outside metal roof sheets having their side edges adapted to drain into said troughs. 90

3. In a car roof, the combination of wooden carlines having metal drain troughs or carlines embedded within the wooden carlines substantially flush with the top thereof, roofing boards supported by the wooden 95 carlines also flush with the top thereof, and outside metal roofing sheets laid on said roofing boards and carlines, and having their side edges adapted to drain into said troughs. 100

4. In a car roof, the combination with carlines having drain troughs, of metal roof sheets having their side edges adapted to drain into said troughs, and a running board saddle formed in separate parts, one portion 105 being fastened to the carlines and having a web extending up between the roof sheets longitudinally of the carline, and the other portion mounted on the web portion above the roof sheets. 110

5. In a car roof, the combination of wooden carlines having U shaped metal carlines embedded therein, roofing boards between said carlines, metal roofing sheets having their edges adapted to drain into 115 said carlines, and a running board saddle formed in two parts, one being bolted longitudinally to the carlines and extending up between the roof sheets, and the other mounted on the first part above the roof 120 sheets for supporting the running boards.

6. In a hatch for car roofs, the combination with roof members, and a hatch frame extending above the roof surface, of metal roofing sheets bent up around the hatch 125 frame, and a metal covering for the top of said hatch frame, said covering extending over the up-turned edges of the roof sheets,

- and being formed in sections of angular bars having interlocking lugs connected together at the corners of the hatch frame.
7. In a hatch for car roofs, the combination with the hatch frame extending above the roof surface, of an angular metal covering for said frame, formed in sections pivotally connected together at the corners of said hatch.
- 10 8. In a car roof, the combination with carlines having drain troughs, of a U shaped metal ridge pole supported thereon and formed in sections with end flanges connected together over the trough of the car lines.
- 15 9. In a car roof, the combination with U shaped metal carlines, of a U shaped metal ridge pole formed in sections with flanges
- riveted together over said carlines and having a drain opening at the bottom between 20 the sections.
10. In a car roof, a U shaped metal ridge pole having lateral and bottom flanges at the end of the ridge extending over the end plate and the facia board of the car. 25
11. In a car roof, a U shaped metal ridge pole having top flanges for supporting metal roof sheets, and lateral and bottom flanges at the end of the ridge extending over the end plate and end facia of the car. 30
- In testimony whereof I have hereunto set my hand.

JOHN L. MOHUN.
